UNITED STATES PATENT OFFICE.

GUSTAV OTTO, OF HOBOKEN, NEW JERSEY, ASSIGNOR TO HIMSELF, FRANCIS H. BAWO, OF NEW YORK, N. Y., HENRY WITTE, OF MONTCLAIR, AND CARL W. F. BAWO, OF NEWARK, NEW JERSEY.

DESIGN FOR A DISH.

SPECIFICATION forming part of Design No. 30,174, dated February 14, 1899.

Application filed January 20, 1898. Serial No. 667,344. Term of patent 7 years.

To all whom it may concern:

Be it known that I, GUSTAV OTTO, a citizen of the United States, residing at Hoboken, Hudson county, and State of New Jersey, have invented and produced a new and original Design for a Dish or Similar Article, reference being had to the accompanying drawings, forming part hereof.

By the term "dish" I mean any concave or hollow vessel, of whatever shape, size, or material, used for serving food at meals.

In the accompanying drawings, Figure 1 is a bottom view of a dish embodying the design. Fig. 2 is a plan or top view of the foot portion. Fig. 3 is a side view of the entire dish.

The edge of the body of the dish is scalloped and beaded. It will be seen that the scallops are approximately pointed at a' , that at each side there are concave curves a^2 , and that intermediate of the concave curves a^2 is a convex curve a^3 . The beading a^4 is made up of a line of dots close to the edge and following the line thereof. From the approximately pointed portions a' of the edge ribs or ridges a^5 , which are approximately, if not exactly, in the position of radii, extend inwardly to a dotted beading a^6 .

The foregoing constitute the essential features of my design. In the foot portion of the dish the ribs a^5 extend outwardly to the edge thereof, which is scalloped to correspond with the edge of the body. This edge is also provided with a dotted beading which extends along the line thereof. To indicate these similarities, I have marked the same letters upon the corresponding parts.

Having described my invention, what I claim as new, and desire to secure by Letters Patent, is—

The design for a dish or similar article substantially as herein shown and described.

Signed by me, at New York, N. Y., this 18th day of January, 1898.

GUSTAV OTTO.
